UNITED STATES PATENT OFFICE.

KARL NITSCHKE, OF BERLIN, GERMANY.

TELESCOPIC LIFTING-GEAR.

1,070,167.

Specification of Letters Patent. Patented Aug. 12, 1913.

Application filed March 26, 1910. Serial No. 551,640.

To all whom it may concern:

Be it known that I, KARL NITSCHKE, a subject of the German Emperor, and residing at Berlin, Germany, have invented certain new and useful Improvements in Telescopic Lifting-Gear, of which the following is a specification.

The subject-matter of my invention is telescopic lifting-gear, whose tubes are pulled apart and drawn together by means of a steel band arranged within the same.

My lifting-gear can be employed for lifting loads of all kinds, people, antennæ for radiotelegraphy, projectors, and also as a mast for signaling purposes, phototelegraphy, and the like.

A primary object of my invention is to provide that the tubes of the lifting-gear are driven positively up and down, and that in both events the tube next in order is only moved when the previous one has been entirely drawn out or entirely drawn in.

Some illustrative embodiments of my invention are represented by way of example in the accompanying drawings, wherein:—

Figure 1 is a vertical section through part of my lifting-gear, three different forms of the steel band being indicated therein; Fig. 2 is a vertical section showing means for guiding the steel band and mechanism for securing the tubes; Fig. 3 is an elevation, partly in section, showing the lifting-gear with the tube elevating and fixing devices, and Fig. 4 shows the automatic fixing device in elevation.

Referring to the drawing, the telescopic tubes 1, 2, 3, 4 are preferably driven positively by the steel band *a* rolled on a roller *l* (Fig. 3) being guided by two press rolls *h*, *h*, pressed together by a screw *i* and driven upwardly by turning the crank-handle *g* secured to one of the rolls. The band is kept most rigid and most suitable for raising loads when it occupies the entire section of the tubes, as shown at *f* in Fig. 1, but is also sufficiently rigid when it is cut tapered, as shown at *u*, and occupies the largest section of the tube at places, whereas, when the band has rectilinear, parallel sides as shown at *v*, and therefore its breadth is only equal to the section of the top telescope tube, it must be made correspondingly thicker.

I prefer to use a steel band which is recessed or shaped step-like as at *f*, fills the

entire diametral section of the tube, and thus cannot move out of position, such a band being able, although relatively weak, to lift considerable loads, that is it acts in the tube like a rigid connecting-rod. In order that the steel band may always have its shoulders in the tubes suitable for the same, the tubes must not be raised and lowered irregularly, but in order.

The tubes are elevated in order by means of the spring-pulled pawl *b* (Fig. 2) pivoted on tube 3; this pawl carries a pivoted pin *d* which can enter into the tubes 1, 2, 3 and lock the same; the pin *d* is withdrawn the thickness of a tube by the shoulders *f* of the rising band coacting with the pawl, whereby one tube is released after another.

The tubes are caused to descend in order by the spring shackles or clamps *q* (Figs. 3 and 4) being automatically released by the pin *m* of the bracket *n*, by which the shackles are automatically tightened as the tubes are elevated. The construction and operation of the shackles will be readily understood from Figs. 3 and 4; the top ends of the tubes are slotted and each carries a shackle *q*, while the largest tube carries a support or bracket *n* carrying a pin *m*. A bolt *s* having on the right a nut and on the left a head passes through the ends of each shackle; outside one end of the shackle is secured a block *p* having a slanting face through which bolt *s* passes, and loose on the latter is an arm *o* having a projection *r* with a slanting face which corresponds to the slanting face on the block *p*. When the shackle is locked the arm *o* is opposite the pin *m* so that when the tube 2 for example moves upward, the shackle *q* is tensioned and the inner tube is fixed, whereas when the tubes descend they are unlocked at the moment when one tube abuts on the head of another. In order to keep the band always in the middle of the rollers I provide a row of perforations in the band (Fig. 2), into which the teeth *w* provided in the middle of the rollers enter.

I claim:—

1. In telescopic lifting-gear, the combination, with a plurality of telescopic tubes arranged one in another, of a flat, steel band therein occupying the greatest diametral section of each tube and filling said section at least one point in the length of each tube when the lifting-gear is extended, and means

105

110

for raising and lowering said band and thereby extending and lowering the lifting-gear.

2. In telescopic lifting-gear, the combination, with a plurality of telescopic tubes arranged one in another, of a flat, steel band therein for coacting with and lifting each tube, means for raising and lowering said band, and a spring-controlled locking device 10 locking said tubes in their closed position and adapted to be actuated by the rising steel band.

3. In telescopic lifting-gear, the combination, with a plurality of telescopic tubes arranged one in another, of a flat, steel band therein for coacting with and lifting each tube, means for raising and lowering said band, a bracket carrying a pin fixed on the lowest tube, the top of each tube being slit 20 longitudinally and carrying an elastic clamp, means on each clamp for tightening the same adapted to coact with and be operated by said pin when the band is raised and lowered.

25 4. In telescopic lifting-gear, the combina-

tion, with a plurality of telescopic tubes arranged one in another, of two press rolls pressed one toward the other in the lowest tube, a centrally-perforated, flat, steel band for coacting with and lifting each tube movable between said rolls, one of the rolls having teeth entering into the band, and a handle secured to the toothed roll.

5. In telescopic lifting-gear, the combination, with a plurality of telescopic tubes arranged one in another, of a tapered, flat, steel band therein occupying the greatest diametral section of each tube and filling said section at least one point in the length of each tube when the lifting-gear is 30 extended, and means for raising and lowering said band and thereby extending and lowering the lifting-gear.

In testimony whereof, I affix my signature in the presence of two witnesses.

KARL NITSCHKE.
